UNITED STATES PATENT OFFICE.

WILLIAM P. KELLOGG, OF TROY, NEW YORK.

CURRY-COMB.

SPECIFICATION forming part of Letters Patent No. 327,695, dated October 6, 1885.

Application filed March 27, 1885. Serial No. 160,146. (No model.)

To all whom it may concern:

Be it known that I, W.M. P. KELLOGG, a resident of the city of Troy, in the county of Rensselaer and State of New York, have invented certain new and useful Improvements in Curry-Combs; and I do hereby declare that the following is a full, clear, and exact description of the invention, that will enable others skilled in the art to which it appertains to make and use the same, reference being had to the accompanying drawings, and to the letters of reference marked thereon, which form a part of this specification.

Similar letters refer to similar parts in the several figures therein.

My invention relates to improvements in curry-combs.

The object of my invention is to easily and quickly secure a duplex handle upon the ends of supports projecting from a curry-comb frame in such a manner as to stiffen and strengthen said supports and produce a convenient and desirable comb.

My invention is an improvement upon the construction shown in Letters Patent of the United States, No. 171,386, dated December 21, 1875, issued to John W. Trussell and myself; and it consists in producing two handle-supports of metal cast integral with the comb-frame, one of which is provided with a projecting tang, and the other with a perforated handle-seat, driving a perforated and ferruled end of a handle upon said tang and firmly riveting the longitudinally middle part of said handle upon said perforated seat.

Figure 1 of the drawings is a view in perspective of my improved comb with handle attached. Fig. 2 is a plan view of same with the handle detached. Fig. 3 is a side elevation of a rivet. Fig. 4 is an end elevation of part shown in Fig. 2.

The metal comb-frame D is provided with the toothed comb-bars a, attached thereto, and with the handle-supports B C, cast integral therewith, the latter being provided with the tang b, integral therewith, and projecting out over the comb toward support B, as shown. Support B is provided with handle-seat S, perforated at i to receive rivet g. The frame-supports and tang are rendered malleable.

The duplex handle A A', provided with the

ferrule a', and a perforation in the ferruled end adapted to receive the tang, is driven onto the tang with sufficient force to render it firmly secure thereon when the middle portion is 55 perforated at a point coincident with the perforation in seat S, in which position the two parts are firmly secured together by a rivet, g, bolt, or screw. It is apparent that when the handle is thus firmly secured to support B 60 it cannot work loose upon the tang b, and the tang being of metal cast integral with support C acts as a brace to keep the supports C and B from vibrating or inclining toward the frame, each part tending to strengthen the 65 other, which is of great importance, in view of the fact that the handle is duplex, the part A' being used interchangeably with the part A, rendering it necessary that the supports B and C should project a considerable distance from 70 the frame D to permit of the easy insertion of the fingers of the operator between the handle A' and the comb-frame.

When the middle part of the handle is fixed to its support by forcing a tang or spur projecting therefrom into the handle, as shown in said Letters Patent, it is not only likely to work loose therefrom, but it generally happens that the handle cannot be driven tightly upon the tang, lest the aperture previously prepared 75 in the middle part of the handle for its support will not be in the proper position to receive the same, or the handle must be driven so far as to split or destroy the handle; but by perforating the handle after it has been driven 80 in the proper distance upon the tang inserted at its end, which is easily done, I am able to secure a perfectly rigid and durable duplex-handled comb.

I am aware that it is not new to secure handles to various implements by means of rivets or by tangs when used separately; but the lightness of material and small size of parts required in a curry-comb render it impracticable to employ rivets in the end of the handle, and the tang alone would soon work loose.

The support B is also required as a thumb- 95 rest in operating the comb, and great lateral strain being exerted upon the supports when the comb is in use the tang is necessary to aid 100 in resisting it.

In the construction of a cheap and durable

duplex-handled comb the rivet and tang are both indispensable, and the efficiency of the one is greatly dependent upon the other.

I am aware that handles have been held by set-screws to concave supports at the top of uprights; also, that a curry-comb handle has been secured to two risers from the tooth-bar frame by the rearwardly-bent ends of said risers entering previously-made holes in the wooden handle; but

What I claim as new, and desire to protect by Letters Patent, is—

In a curry-comb, the combination, with the

frame D, having the support B, provided with the concave seat S, and the support C, provided with the tang b, of the duplex handle A A', provided with the ferrule d', the handle being driven onto the tang and held to the seat by a pin, g, passing through a hole in the seat and handle, substantially as described. 20

In testimony whereof I have hereunto set my hand this 24th day of March, 1885.

WILLIAM P. KELLOGG.
